N. E. TAYLOR

SURFACE CONDENSER

Filed April 23, 1924

Inventor

Newell E. Taylor

By his Attorney

Herbert G. Oden

UNITED STATES PATENT OFFICE.

NEWELL E. TAYLOR, OF BROOKLYN, NEW YORK, ASSIGNOR TO INGERSOLL-RAND COMPANY, OF JERSEY CITY, NEW JERSEY, A CORPORATION OF NEW JERSEY.

SURFACE CONDENSER.

Application filed April 23, 1924. Serial No. 708,352.

To all whom it may concern:

Be it known that I, NEWELL E. TAYLOR, a citizen of the United States, and a resident of Brooklyn, county of Kings, city and

5 State of New York, have invented a certain Surface Condenser, of which the following is a specification, accompanied by drawings. This invention relates to condensers, but more particularly to that type of condenser 10 known as surface condenser, wherein a plurality of water tubes extend through a chamber transverse to the current of steam to be condensed and provide cooling surface for absorbing heat to condense the steam.

15 The increase in the temperature of the water passing through the tubes results in a smaller temperature difference between the steam and the water, and therefore a smaller capacity for condensation at the discharge end of the tubes than at the inlet end. The increase in water temperature and therefore the decrease in capacity for condensation is progressive from the water inlet end of the tubes to the water outlet end.

20 In order that the full capacity for condensation of all the tube surface be utilized, it is therefore necessary that a greater amount of steam shall flow to the end of the condenser at which water enters the tubes than to the water discharge end of the condenser.

25 With the same drop in steam pressure from the point of steam entrance to the point of air extraction for all transverse cross sections throughout the length of the condenser sufficient steam will not flow across the cooler ends of the tubes to prevent relatively stagnant flow across the lower tubes at their cooler ends unless the resistance to flow of steam is less at the 30 cooler than at the warmer ends of the tubes. The relatively stagnant flow results in lower rate of heat transfer from the steam to the water through the lower tubes at their cooler ends.

35 40 It is an object of this invention to enable both ends of the condenser to be operated at full capacity, thereby utilizing the entire steam condensing surface of the water tubes and resulting in an equal depth of 45 penetration of the steam uniformly throughout the length of the condenser.

The invention will be more clearly understood by referring to the drawing, which illustrates in vertical longitudinal section,

a water tube surface condenser in accordance with the practice of this invention. 55

The shell or casing A is provided with an inlet B for the steam to be condensed and an outlet C through which the condensate and incondensable gas is removed by suitable evacuating apparatus. A plurality of water tubes D extend longitudinally in the casing A substantially transverse to the direction of steam flow and are supported at the inlet water head E by means of a tube sheet F and at the discharge head G in a tube sheet H. A central tube supporting plate J prevents the tubes from sagging and vibrating.

In order to prevent the steam from penetrating more deeply at the warmer end than at the cooler end of the condenser, which would result in wasted tube surface at the lower part of the cooler end of the condenser, the tubes D are arranged to converge 75 somewhat toward the warmer end. This is accomplished preferably by utilizing straight water tubes but spaced closer together in the tube sheets H than in the tube sheets F. The convergence or inclination 80 of the tubes with respect to each other is uniform from end to end. Thus, while the area exposed to the steam by the pipes is the same at all cross sections, the interstices or area permitted for the steam to pass between the tubes, gradually diminishes from the cool end of the tubes toward the warm end and the resistance to the steam flow uniformly increases in that direction. 85

Thus, with a given degree of vacuum at 90 the outlet C, a greater volume of steam will pass through the condenser over the tubes D at the cooler end than at the warmer end, and if the convergence of the tubes and resulting resistance to the flow of steam 95 be properly arranged the penetration of the steam should be equal at all points throughout the length of the condenser. If steam is being supplied at the inlet B in the quantity for which the condenser is designed, such steam should penetrate to the lowermost bank of tubes D both at the cool end and at the warm end and points in between. Preferably, the casing A is tapered to conform with the convergence of 100 the tubes D. 105

I claim:

1. A surface condenser, comprising a cas-

ing having a steam inlet and an outlet for condensate and non-condensable gases, and a plurality of water tubes extending longitudinally therethrough transverse to the direction of steam flow, said tubes being convergent toward the warmer end of the condenser to provide substantially the same condensing surface at all cross sections and diminishing area for the steam passage 10 therebetween in the direction of the warmer end of the condenser, whereby the steam is caused to penetrate to uniform depth throughout the condenser.

2. A surface condenser, comprising a casting having a steam inlet and an outlet for

condensate and non-condensable gases, and a plurality of water tubes extending longitudinally therethrough transverse to the direction of the steam flow, said tubes being uniformly convergent from the cooler end of 20 the condenser to the warmer end to provide substantially the same condensing area for the steam at all cross sections and uniformly diminishing the area for the passage of steam therebetween, whereby the steam is 25 caused to penetrate to uniform depth throughout the condenser.

In testimony whereof I have signed this specification.

NEWELL E. TAYLOR.
